E. M. Bentley

UNITED STATES PATENT OFFICE.

JOSEPH M. BOSENBURY, OF PEORIA, ILLINOIS, ASSIGNOR TO CONSOLIDATED CAR-HEATING COMPANY, OF ALBANY, NEW YORK, A CORPORATION OF WEST VIRGINIA.

CAR HEATING BY CONTROLLER RHEOSTATS.

Application filed January 27, 1928. Serial No. 249,981.

For a detailed description of the present form of my invention, reference may be had to the following specification and to the accompanying drawing forming a part thereof.

5 My invention consists in providing the controller for the propelling motors of an electric car with a double set of rheostatic resistances, one set being located under the car in the usual manner and the other set being divided 10 into sections, the several sections being distributed through the body of the car in suitable casings, preferably in the same casings which contain the usual electric heaters and mounted in the same manner as said heaters. 15 Between the controllers and the two sets of rheostatic resistances I provide a switch for connecting the sets to the controllers alternately. I am thus able to utilize one of said sets as a supplementary means of heating the 20 car in extreme cold weather, while the controller is at all times equipped with the necessary resistors for modifying the car speed.

Referring to the drawing, R^5 , R^4 , R^1 , R^2 , R^3 , represent wires extending between the 25 two controllers at the opposite ends of the car respectively. F is a selector switch, by means of which the said wires may be connected respectively to the wires r^1 , r^2 , r^3 , r^4 , r^5 , which lead to the resistor grid A , B , C , D of the 30 usual rheostat G under the car body, or, when turned in the opposite direction, will connect them to the corresponding wires R^1 , R^2 , R^3 , R^4 , R^5 , leading to the car heaters.

In the body of the car are the normal 35 heater sections numbered from 1 to 20, which are shown as connected in series between the trolley T and the ground by means of the hand-switch E and each contained in a suitable casing for guarding it and enabling it 40 to radiate its heat into the car. Certain ones of this series of casings are shown as containing, in addition to the normal heater-coil section, a section of controller rheostat. Of these the ones marked 1^a , 1^b , 1^c correspond to grid-section B of the under-car rheostat; those marked 2^a , 2^b , 2^c correspond to grid-section A ; those marked 3^a , 3^b , 3^c correspond to grid-section C and those marked 4^a , 4^b , 4^c corre-

spond to grid-section D . Thereby these sections, although of wire-coils sized and distributed for heating purposes, may also serve in groups as a controller-rheostat to graduate the car speed with the same effect as the grid C .

What I claim as new and desire to secure 50 by Letters Patent is:

1. A controller for electric cars having two sets of resistances, one a resistance outside of the car body, the other a resistance inside the car body for car heating, and a switch for 55 connecting the sets to the controller alternately.

2. A controller for electric cars having a resistance outside the car body in the form of a grid, the other a resistance inside the car body having a length of wire corresponding to a grid section divided into a set of car heaters each enclosed in a casing and a switch for connecting the two resistances to the controller alternately.

3. A controller for electric cars having two sets of resistances, one composed of coil sections within the car body contained in casings which also contain heating resistance in a separate heating circuit and a switch for connecting the two sets to the controller alternately.

4. In a car heater, a casing, a section of the car motor resistors enclosed within said casing, and a heater resistance also enclosed within said casing.

5. A car heating system comprising a motor rheostat, a series of resistances contained in a permanent heater circuit between the trolley and ground, a second series of supplemental heater resistances in series with the motor and arranged to serve as motor rheostat resistors, and a switch for selectively connecting the motor circuit with said rheostat or with said supplemental heater resistances.

6. A combined heating and controlling system for an electric car comprising a series of wires connecting the controllers at opposite ends of the car, two branches therefrom, each containing a series of resistance sections suitable for regulating the car motors, one series

being contained in heater casings within the car body, and a switch for connecting the two branches to the controllers alternately.

7. A combined car-heating and controlling system comprising controllers at each end of the car, a series of wires connecting them, and two branches therefrom, one branch containing a sectional resistance grid outside the

car body and the other containing a group of resistance sections within the car body corresponding to each grid section and separately enclosed in heater casings, together with a switch for connecting the two branches with the controllers alternately.

JOSEPH M. BOSENBURY.
